The ornamental design for an injector, as shown and described.

DESCRIPTION

FIG. 1 is a perspective view of an injector showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right elevation side view thereof.

The drawings include light grey shade lines that represent contour and not surface ornamentation.

The broken lines illustrate structure or features which form no part of the claimed design.
